UNITED STATES PATENT OFFICE.

HENRY FOREST, OF EAST ST. LOUIS, ILLINOIS, ASSIGNOR TO OBEAR-NESTER GLASS COMPANY, A CORPORATION OF MISSOURI.

DESIGN FOR A PRESCRIPTION-BOTTLE.

SPECIFICATION forming part of Design No. 36,001, dated August 12, 1902.

Application filed May 10, 1902. Serial No. 106,841. Term of patent 14 years.

To all whom it may concern:

Be it known that I, HENRY FOREST, a citizen of the United States, and a resident of the city of East St. Louis and State of Illinois, have invented a new and original and ornamental Design for a Prescription-Bottle, of which the following is a specification.

Figure 1 is a top view of a bottle embodying my design. Fig. 2 is front view thereof. Fig. 3 is a horizontal cross-section on the line 3 3 of Fig. 2, and Fig. 4 is a side view of said bottle.

As shown in the accompanying drawings, my bottle has six faces. One of those faces, 1, constituting the back of the bottle, is flat, and the opposite face 2, constituting the front of the bottle, is a convex curve of large radius. The four remaining faces are arranged in two groups of two faces each. The two faces 3 4 of each group are flat and arranged to meet at an obtuse angle, so as together to constitute one side of the bottle. The corners

formed by the meeting of adjacent edges are rounded. The shoulder 5 of the bottle is formed of convex curves, which merges into 25 the edge at the middle of each side, but which meets the body at other points at an angle, whereby the front and back sides of the bottle are arched at their upper end 6. The curve of the shoulder reverses to a concave 30 curve, which continues nearly to the top of the circular neck 7 of the bottle, where it merges into a cylinder, and is then turned outwardly to form the lip 8 of the bottle.

Having described my invention, what I 35 claim as new, and desire to secure by Letters Patent, is—

The ornamental design for a prescription-bottle, as herein shown and described.

East St. Louis, Illinois, May 7, 1902.

HENRY FOREST.
